Primary Examiner — Eliza Z Harvey

Assistant Examiner — Kayla Marie Bennett

(57) **CLAIM**

The ornamental design for a furniture leg protector, as shown and described.

DESCRIPTION

FIG. 1 is a perspective view of a furniture leg protector showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines immediately adjacent the shaded areas represent the bounds of the claimed design while all other broken lines are directed to portions of the furniture leg protector that form no part of the claim.

1 Claim, 8 Drawing Sheets
